UNITED STATES PATENT OFFICE.

LEONARD C. MOÏSE AND ANTHONY OLIVER PONS, OF COVINGTON, LOUISIANA.

WRENCH.

1,099,811.

Specification of Letters Patent.

Patented June 9, 1914.

Application filed December 6, 1913. Serial No. 805,087.

To all whom it may concern:

Be it known that we, LEONARD C. MOÏSE and ANTHONY OLIVER PONS, citizens of the United States, residing at Covington, in the 5 parish of St. Tammany and State of Louisiana, have invented new and useful Improvements in Wrenches, of which the following is a specification.

The present invention relates to improvements in wrenches, and has for its object to provide a comparatively simple and inexpensive device of this character in which gripping jaws may be readily clamped in engaging position, and one in which the jaws 10 will be moved alternately to open position for engagement with a nut or bolt.

With the above recited objects in view, and others which will appear as the nature of the invention is more fully understood, 15 the improvement resides in the construction, combination and arrangement of parts set forth in the following specification and falling within the scope of the appended claims.

In the drawing: Figure 1 is a perspective 20 view of a wrench constructed in accordance with the present invention, Fig. 2 is a sectional elevation of the wrench, the section being taken centrally and longitudinally 25 thereof and illustrating the compression member or sleeve acting upon the rear or tail portion of the jaw beyond its pivot for swinging the jaw to an open position, and Fig. 3 is a transverse sectional view on the line 3—3 of Fig. 2, and Fig. 4 is a perspective 30 view of a modified form of the sleeve.

Referring now to the drawing in detail, 1 1 designates the body or shank of the wrench which has one of its ends terminating in a fixed jaw 2. The jaw, at its end, is provided 5 with a longitudinally extending depression 3, and upon its inner face at a suitable distance from its ends with a transversely arranged depression 4. The shank 1 terminates in a reduced portion 5 preferably of a 10 rectangular form in cross section and designed for engagement by a brace, handle or other operating member. The shank 1 is formed with a longitudinally arranged depression 6 upon its end opposite to that 15 formed with the gripping jaw 2, the said depression entering the outer face of the shank and the lower wall of said depression is inclined from the end of the said shank toward the transverse wall provided by the 20 depression, as indicated by the numeral 7. Pivoted, as at 8, between the walls formed

by the depression 6 is the movable or swinging jaw 9 which is provided with a transverse depression 10 and a longitudinally V-shaped depression 11, the said depressions adapted 25 to register with the depressions 3 and 4, when the jaw 9 is swung upon the jaw 2. The pivot of the jaw 9 is arranged near the end of the shank 1, and the said jaw to the rear of its pivot is provided with what I 30 term a reduced tail 12. The jaw 9 is of a width equaling the jaw 2 and the distance between the walls provided by the depression 3 is less than the width or thickness of the jaws, so that the tail 12 is reduced, providing the jaw 9 with shoulders 13 which 35 abut with the shoulders formed on the ends of the walls at the opposite sides of the depression 6. The lower wall of the tail is inclined from its juncture with the jaw proper 40 to the end of said tail, so that the jaw 9 may be swung a comparatively great distance away from the jaw 2. The outer face of the tail 12, from its juncture with the jaw proper 45 is enlarged to provide a declivous surface 14, 50 the said inclined enlargement sloping from the end of the tail to the juncture of the tail with the jaw proper.

The numeral 15 designates a sleeve or 55 compression member which is arranged upon both of the jaws, the said member having its outer face, opposite the outer face of the jaw 9 beveled inwardly toward its bore, as indicated by the numeral 16, the said beveled portion serving as an engaging surface for 60 the jaw when the latter is swung to its outer position. The shank 1, to the rear of its depression 6 is provided with shoulders 17 which are adapted to contact with and prevent the movement of the sleeve 15 toward 65 the reduced portion of the shank. The jaw 9 is of a greater thickness at its outer end than at its juncture with the tail piece 12, the inclination from the said end being gradual, but sufficient to prevent the sleeve 15 from 70 being withdrawn in an outward direction from its engagement with the jaws 2 and 9. It will be noted that when the sleeve or compression member 15 is moved toward the 75 ends of the jaws, the same will force the jaw 9 toward the jaw 2 and the frictional engagement between the said member 15 and the jaw 9, owing to the inclined surface 16, will hold the said jaw 9 at any adjusted position with relation to the jaw 2, and furthermore, that upon a rearward movement 80 of the member 15, the same will travel over 85

the declivous surface 14 upon the outer face of the tail, and thus swing the jaw 9 to an open position.

In order to reinforce the side walls provided by the depression 6, and also to retain the pivot 8 against accidental removal, we have formed this portion of the wrench, forward of the shank 1, with a continuous depression A within which is received a reinforcing band B. The band lies flush with both the sides and the faces of this portion of the wrench, so as not to interfere with the movement of the compression member 15. The upper portion of the tail of the movable or swinging jaw 9 is provided with a depression C so that the member of the band arranged across the said tail will not contact with the tail. The band also serves as a means for forcing the side walls provided by the depression 6 into frictional engagement with the sides of the tail 12.

In Fig. 4 we have illustrated a form of sleeve which may be employed. This sleeve, designated by the numeral 15^a, comprises a substantially U-shaped member or yoke, which is preferably constructed of metal so that the sides 15^b will exert a tension toward each other and frictionally contact with both the stationary and pivoted jaw, when the sleeve is arranged in operative position. The arms 15^b are provided adjacent their free edges with approximately centrally disposed alining openings through which pass the stems of headed pivots 50, which hingedly sustain a top or plate 51 between the arms of the sleeve and in contacting relation with the outer face of the jaw 9. The plate 51, it will be noted, will tilt upon its pivots and lie flat upon the outer face of the jaw 9, when the sleeve is slid to force the said jaw into tight engagement with an article between the jaws, and the opposite lower corners of the plate are beveled or rounded so that no resistance will be offered when the sleeve is moved over the outer declivous surface 14 of the tail 12 of the jaw 9 or the shoulders or transverse walls provided by the depression C.

From the above description, taken in connection with the accompanying drawing, the simplicity of the device as well as the advantages thereof will, it is thought, be perfectly apparent to those skilled in the art to which such inventions appertain without further detailed description.

Having thus described the invention, what we claim is:

1. In a device of the class described, a shank having a longitudinally extending fixed jaw, the end of the shank opposite the fixed jaw being recessed, a swinging jaw having a reduced tail portion received within the recess and pivoted upon the opposite walls provided by the recess, a slidable compression member upon the jaws of the

wrench, and the tail of the swinging jaw, to the rear of its pivot having an inclined surface adapted to be contacted by the compression member to swing the said jaw to an open position.

2. In a device of the class described, a shank having a shoulder, a movable jaw integrally formed with the shank and extending beyond the shoulder, the end of the shank to the opposite sides of the jaw and forward of the shoulder having a depression which communicates with its end and which is inclined, a movable jaw, said movable jaw having a reduced tail piece which is adapted to be arranged between the walls of the depression and to be pivoted within the depression adjacent the outer end of the shank, the inner face of the tail being inclined from its juncture with the jaw to the end of the tail, the outer face of the tail having an inclined surface from its end to its juncture with the jaw, the outer face of the jaw being also inclined outwardly from the tail to its end, the ends of both of the jaws having sockets, the inner faces of both of the jaws having transverse V-shaped depressions which are adapted to aline, a compression sleeve slidably mounted upon the jaws, said sleeve having its face opposite the outer face of the swinging jaw beveled inwardly to its bore, and the said sleeve when moved toward the shoulder of the shank and opposite the pivot of the jaw adapted to contact with the inclined outer face of the tail to swing the movable jaw to an open position.

3. In a device for the purpose described, a shank having a longitudinally extending fixed jaw, the said shank at its juncture with the jaw having a recess opposite the said jaw, a swinging arm having a reduced tail portion arranged within the recess and pivotally secured to the opposite walls thereof, the outer face of the tail being inclined outwardly, a band surrounding the recessed portion of the shank and a portion of the tail of the pivoted jaw and inclosing the pivot of the jaw, and a slidable compressible member upon the jaws and adapted to contact with the tail of the pivoted jaw to swing the outer end of the pivoted jaw away from the stationary jaw.

4. In a wrench of the class described, a substantially rectangular shank having a reduced longitudinally extending fixed jaw, the shank opposite the fixed jaw having a longitudinally arranged recess, a jaw having a reduced longitudinally extending tail which is arranged within the recess and pivoted between the walls provided thereby, a tail having its outer face inclined from its juncture with its jaw to its outer end, a reinforcing band received within a recess in the shank and a recess within the tail surrounding said shank and tail and contacting

with the pivot of the swinging jaw, a sleeve mounted for slidable movement upon the wrench and surrounding the jaws thereof, said sleeve including a pivoted plate which
5 is adapted to bear against the outer face of the pivoted jaw, all substantially as and for the purpose set forth.

In testimony whereof we affix our signatures in presence of two witnesses.
